UNITED STATES PATENT OFFICE.

KARL D. SMITH, OF BATTLE CREEK, MICHIGAN, ASSIGNOR TO UNION STEAM PUMP COMPANY, OF BATTLE CREEK, MICHIGAN.

PUMP.

Application filed December 20, 1926. Serial No. 155,932.

The main objects of this invention are:

First, to provide an improved high pressure pump assembled as a unit which is very compact and one in which the most of the 5 moving parts are housed or inclosed and effectively protected and lubricated.

Second, to provide an improved pump which is well adapted for use in creameries and the like where freedom from dirt and 10 grease is highly desirable.

Third, to provide an improved pressure pump embodying these advantages which is comparatively economical and at the same time durable.

15 Objects pertaining to details and economies of construction and operation of my invention will definitely appear from the detailed description to follow. The invention is clearly defined and pointed out in the 20 claims.

A structure embodying the features of my invention is clearly illustrated in the accompanying drawing forming a part of this application, in which:

25 Fig. 1 is a side elevation of a structure embodying the features of my invention as especially designed by me in an apparatus for treating milk known as a "viscolizer".

Fig. 2 is a fragmentary view partially in 30 vertical longitudinal section on a line corresponding to line 2—2 of Fig. 3.

Fig. 3 is a fragmentary view partially in horizontal section on a line corresponding to line 3—3 of Figs. 2 and 4.

35 Fig. 4 is a fragmentary perspective view showing the arrangement of the auxiliary housing for the driving connections.

Fig. 5 is a perspective view of the eccentrics and of the driven gear connected there- 40 to.

Fig. 6 is a fragmentary perspective view with the cap or top portion of the housing removed, further illustrating the relation of the parts.

45 Referring to the drawings, in the embodiment illustrated, I provide a base 1 having a chamber or housing 2 therein for certain of the mechanisms as will be hereinafter described, this housing having a removable top 50 or cap 3.

The structure illustrated is especially de- 55 signed by me for a milk treating apparatus, known commercially as a "viscolizer", this unit being designated generally by the num-

no part of my present invention, I do not fully illustrate nor describe the same herein.

This unit includes pumps having plunger rods 5 which are arranged through stuffing boxes 6 carried by a closure plate 7 for the 60 opening 8 at the end of the housing. The mounting of the stuffing box upon the plate 7 instead of within the wall housing is a matter of manufacturing convenience and also facilitates the assembling and disassem- 65 bling of the parts.

The housing 2 is adapted as a lubricant receptacle, it having a curved bottom 2' (see Fig. 2), the purpose of which will appear as the description proceeds.

70 The end walls of the housing are provided with bearing-like bosses 9 and 10 in which the non-rotating shaft 11 is supported, the shaft being held against rotation by the set screw 12. These bosses are open at their ends 75 to permit the introduction and removal of the shaft, the openings being closed by the plates 13.

The end walls of the housing are also provided with bearings not detailed for the 80 driving shaft 14, the outer end of one of the bearings being closed by the plate 15, the shaft projecting through the other bearing to receive the sprocket wheel 16. This 85 sprocket wheel is connected to the motor indicated generally by the numeral 17 mounted on the bracket 18 on the housing. An auxiliary housing 19 is provided for the driving connections of the motor to the shaft 14.

90 On the shaft 11, I mount a plurality of eccentrics 20, these eccentrics being, in the embodiment illustrated, formed integrally and lying side by side without space between them and being suitably indexed relative to each other.

95 The gear 21 is, in the embodiment illustrated, also formed integrally with the eccentrics. The several connected eccentrics, in effect, constitute an eccentric shaft, and 100 for brevity, I have herein designated the same by the broad term "cam shaft." The gear 21 meshes with a pinion 22 on the shaft 14 so that the gear 21 and eccentrics are driven as a unit or single cam shaft.

105 The pitmen or eccentric rods 23 are provided with suitable straps 30 embracing the eccentrics, these straps lying side by side and in sliding bearing engagement. One of the outer straps is supported by a shoulder 110

31 at the inner side of the gear 21 and the other by a flange-like collar 32, the collar being also formed integrally with the eccentrics.

5 The pitmen or eccentric rods 23 are connected to the slides or cross heads 25 by the pins 24. These cross heads are arranged side by side in coacting sliding contact upon the slideway 26, constituting a portion of the bottom of the housing, this part being suitably elevated above the lubricant well portion 2' of the housing bottom. The slide 26 has a flat face which is, as illustrated, common to all of the cross heads.

15 Parallel slideway end members 27 project upwardly from the slideway and constitute side members or supports for the outer cross heads. The slideway top member 28 has a flat inner face common to all of the cross heads and is bolted upon the end members 27. This top has an upwardly projecting wall 33 at its rear edge and ends, a portion of its forward edge, at 34, lying close to the periphery of the gear 21 so that a considerable portion of the lubricant picked up by the gear is discharged upon the slideway top member, the gear acting as a pump providing a constant supply of lubricant when the machine is running.

30 To make this gear efficient as a pump, the housing is suitably conformed to the gear, as shown in Fig. 2, that is, the periphery of the gear throughout its greater portion is quite close to the wall or housing.

35 The bottom of the slideway projects slightly beyond the forward edge of the slideway top so that the lubricant discharged upon the slideway will flow off the front edge of the top upon the bottom.

40 To further distribute the lubricant to the cross heads, the top is provided with an opening 29 above the path of each cross head. The result is that a large amount of lubricant is continuously supplied to the cross head. The eccentrics are also kept thoroughly lubricated, the eccentrics dipping into the lubricant on the down-stroke, the lubricant being carried up and delivered between the coacting faces of the eccentric 45 straps, and also the lubricant flows down the connecting rods 23 when the same are forwardly inclined to carry lubricant to the pins 24, and when rearwardly inclined, as on the down-stroke of the eccentrics, the lubricant is directed to the eccentrics. Thus 50 all of the parts are very efficiently lubricated, the structure is very compact and the number of parts is minimized.

55 Further, the moving parts are so encased that the escape of lubricant is effectively prevented, thus well adapting my improvements for such uses as in the "viscolizer" which is used, as stated, in the treatment of milk where cleanliness is greatly to be 60 desired.

A further advantage is that the parts are economical to produce and very easily assembled, and the structure is well adapted for high pressure pumps.

Having thus described my invention what 70 I claim as new and desire to secure by Letters Patent is:

1. In a structure of the class described, the combination of a main housing adapted as a lubricant receptacle, a driving shaft disposed to project from said housing at one end and provided with a driving pinion within the housing, a driven gear meshing with said pinion, a plurality of eccentrics connected to said driven gear, a spindle on which said driven gear and eccentrics are rotatably mounted, a pitmen coacting with said eccentrics, a cross head way base member integral with said housing and constituting a portion of the bottom wall thereof, 75 cross heads disposed on said way base member side by side in sliding coacting relation, way side members on said base coacting with the outer sides of the outer cross heads, a way top member removably mounted on said way side members and disposed with its front edge adjacent to said gear so that the gear constitutes a pump discharging the lubricant upon said way top member, said way top member being provided with openings 80 for the passage of lubricant therethrough to said cross heads, a plurality of piston rods projecting through said main housing and connected to said cross heads, a motor mounted on said main housing, driving connections for said motor to said driving shaft disposed at the side of the main housing, and an auxiliary housing for said driving connections and the projecting end of said driving shaft.

2. In a structure of the class described, the combination of a main housing adapted as a lubricant receptacle, a driving shaft disposed to project from said housing at one end and provided with a driving pinion 110 within the housing, a driven gear meshing with said pinion, a plurality of eccentrics connected to said driven gear, a spindle on which said driven gear and eccentrics are rotatably mounted, pitmen coacting with 115 said eccentrics, a cross head way base member integral with said housing and constituting a portion of the bottom wall thereof, cross heads disposed on said way base member side by side in sliding coacting relation, 120 way side members on said base coacting with the outer sides of the outer cross heads, a way top member removably mounted on said way side members and disposed with its front edge adjacent to said gear so that the gear constitutes a pump discharging the lubricant upon said way top member, said top member being provided with openings 125 for the passage of lubricant therethrough so said cross heads, and a plurality of piston 130

rods projecting through said main housing and connected to said cross heads.

3. In a structure of the class described, the combination of a main housing adapted as a lubricant receptacle, a driving shaft disposed to project from said housing at one end and provided with a driving pinion within the housing, a driven gear meshing with said pinion, a plurality of eccentrics connected to said driven gear, a spindle on which said driven gear and eccentrics are rotatably mounted, pitmen coacting with said eccentrics, a cross head way base member integral with said housing and constituting a portion of the bottom wall thereof, cross heads disposed on said base member side by side in sliding coacting relation, way side members on said base coacting with the outer sides of the outer cross heads, a plurality of piston rods projecting through said main housing and connected to said cross heads, a motor mounted on said main housing, driving connections for said motor to said driving shaft disposed at the side of the main housing, and an auxiliary housing for said driving connections and the projecting end of said driving shaft.

4. In a structure of the class described, the combination of a housing, a spindle within said housing, a plurality of integrally formed eccentrics disposed side by side in non-spaced relation rotatably mounted on said spindle, a gear formed integrally with said eccentrics, a plurality of cross heads disposed side by side in sliding coacting relation, a plurality of pitmen provided with eccentric straps coacting with said eccentrics, said straps being disposed in side by side bearing relation, a slideway for said cross heads comprising a base member having a flat face common to all of the said cross heads, way side members coacting with the outer sides of the outer cross heads and a way top mounted on said way side members disposed with its front edge in a plane at the rear of the front edge of said way base member, said top member being disposed with a portion of its edge in close proximity to said gear so that the gear constitutes a pump discharging lubricant upon said top, said top being provided with openings above the path of said cross heads, said housing constituting a lubricant receptacle and being conformed to said gear.

5. In a structure of the class described, the combination of a housing, a spindle within said housing, a plurality of integrally formed eccentrics disposed side by side in non-spaced relation rotatably mounted on said spindle, a gear formed integrally with said eccentrics, a plurality of cross heads disposed side by side in sliding coacting relation, a plurality of pitmen provided with eccentric straps coacting with said eccentrics, said straps being dis-

posed in side by side bearing relation, a slideway for said cross heads comprising a base member having a flat face common to all of the said cross heads, way side members coacting with the outer sides of the outer cross heads, and a way top mounted on said way side members disposed with its front edge in a plane at the rear of the front edge of said way base member, said top member being disposed with a portion of its edge in close proximity to said gear so that the gear constitutes a pump discharging lubricant upon said top, said housing constituting a lubricant receptacle and being conformed to said gear.

6. In a structure of the class described, the combination of a housing adapted as a lubricant receptacle, a gear, a plurality of eccentrics disposed side by side in non-spaced relation rotatable with said gear, a plurality of cross heads disposed side by side in coacting sliding relation, a plurality of connecting rods provided with eccentric straps coacting with said eccentrics, said straps being disposed in side by side bearing relation, a slideway for said cross heads comprising a base member having a flat face common to all of the said cross heads, way side members coacting with the outer sides of the outer cross heads, and a way top mounted on said way side members disposed with its front edge in a plane at the rear of the front edge of said way base member, said top member being disposed with a portion of its edge in close proximity to said gear so that the gear constitutes a pump discharging lubricant upon said top.

7. In a structure of the class described, the combination of a housing adapted as a lubricant receptacle, a plurality of eccentrics disposed side by side in non-spaced relation, a plurality of cross heads disposed side by side in coacting sliding relation, a plurality of connecting rods provided with eccentric straps coacting with said eccentrics, said straps being disposed in side by side bearing relation, a slideway for said cross heads comprising a base member having a flat face common to all of the said cross heads, way side members coacting with the outer sides of the outer cross heads, and a way top mounted on said way side members disposed with its front edge in a plane at the rear of the front edge of said way base member, and a means for delivering lubricant to said way top member.

8. In a structure of the class described, the combination of a housing adapted as a lubricant receptacle, a gear, a plurality of eccentrics disposed side by side rotatable with said gear, a plurality of cross heads disposed side by side in coacting bearing relation, a plurality of connecting rods provided with eccentric straps coacting with said eccentrics, said straps being disposed in

side by side bearing relation, and a slide-way common to all of said cross heads and provided with a top disposed in close proximity to said gear so that the gear constitutes a pump discharging lubricant upon said top, the top constituting a distributing means for the lubricant to said cross heads.

9. In a structure of the class described, the combination of a housing adapted as a lubricant receptacle, a crank shaft provided with a gear, coating connecting rods, connecting rod cross heads disposed side by side in sliding coating relation, a slideway for said cross heads comprising a base member having a flat face common to all of the said cross heads, and way side members coating

with the outer sides of the outer cross heads, and a way top mounted on said way side members disposed with its front edge in a plane at the rear of the front edge of said way base member to discharge lubricant thereon and upon said connecting rods, said top member being disposed with a portion of its edge in close proximity to said gear so that the gear constitutes a pump discharging lubricant upon said top, said top being provided with openings above the path of said cross heads.

In witness whereof I have hereunto set my hand.

KARL D. SMITH.
